DES. 18.767

UNITED STATES PATENT OFFICE.

HOLMES SMITH AND FRANK A. SEIFERT, OF ST. LOUIS, MISSOURI, ASSIGNORS TO THE BRIDGE AND BEACH MANUFACTURING COMPANY, OF SAME PLACE.

DESIGN FOR A HEATING-STOVE.

SPECIFICATION forming part of Design No. 18,767, dated November 27, 1888.

Application filed September 13, 1888. Serial No. 285,342. Term of patent 14 years.

To all whom it may concern:

Be it known that we, HOLMES SMITH and FRANK A. SEIFERT, of St. Louis, Missouri, have jointly invented and produced a new and original Design for a Heating-Stove, of which the following is a full, clear, and exact description, reference being had to the accompanying engraving, forming part thereof, in which the newly-designed stove is shown in perspective.

This newly-designed stove belongs to a familiar class, the leading external feature of which is a horizontally-arranged oval or approximately oval body having a door and sometimes a hearth at one of its ends and supported upon legs arranged at the ends of the body. In the present instance the stove-body A is more square than oval in vertical cross-section, and the ends B B' are carried up straight at the side edges of the end, and the top of the end is rounded. The legs C in front elevation taper downward and in side elevation curve outward and terminate in a scroll, c. D represents the hearth, and E represents the door in the end B'. One of the features of the design is the flutings appearing upon the legs, the ends, and the body of the stove. The flutings e' upon the legs are arranged in tiers, those in the lowest tier being longer vertically and those in the upper tiers being shorter, and also respectively wider, and respectively above and beneath the upper tier are rows of leaf ornaments, substantially as shown. The flutings b upon the ends B B' are arranged along the edge of the end, and may be styled "plain" flutings, substantially as shown. The flutings e upon the door E are arranged horizontally at the side and vertically at the top of the door, and the two sets are separated at the upper corners of the door, substantially as shown. A medallion, e', upon a smooth panel, e'', appears in the space included by the two sets of flutings e.

Another feature of the design is the panels a a', of oak-leaf and oak-apple ornamentation, upon the side of the body A and at the sides, respectively, of the door a'.

Upon the top of the stove-body appear flutings a' and leaves a'', the flutings surrounding the central raised portion, a', which supports

the urn F, and the leaves a' surrounding the flutings, substantially as shown.

The stove usually has a side rail, G, whose top g is open-work of a Moorish design.

There may be pinnacles H upon the ends B B', consisting of a shell, n, with a sea-weed ornamentation, h', at each side thereof, substantially as shown.

We claim—

1. The design for a heating-stove herein shown and described, the same consisting of the horizontally-extended square body with the ends having the straight side edges and rounded top, and having the superimposed ornamentation of flutings b e, the tapering legs bearing the ornamentation of flutings, and the hearth.

2. In a design for a heating stove, the body herein shown and described, the same consisting of the superimposed ornamentation representing oak-leaves and oak-apples upon the side of the body.

3. In a design for a heating stove, the top of the body herein shown and described, the same consisting of the superimposed ornamentation representing flutings a' and leaves a'', arranged as described upon the body-top.

4. In a design for a heating-stove herein shown and described, the end of the same, consisting of the body end made straight at its side edges and rounded at the top, and having the superimposed ornamentation representing the flutings b and the flutings e, arranged as described.

5. In a design for a heating stove, the legs herein shown and described, the same consisting of the tapering leg and having the superimposed ornamentation representing the flutings arranged in tiers, as described.

6. In a design for a heating-stove, the stove-door herein described and shown, the same consisting of the superimposed ornamentation representing flutings arranged horizontally and vertically, as described, and around the smooth panel.

Witness our hands this 22d day of June, 1888.

HOLMES SMITH.
Witnesses: FRANK A. SEIFERT.
